UNITED STATES PATENT OFFICE.

WILLIAM C. LARSON AND CHARLES P. WEGNER, OF TWO HARBORS, MINNESOTA.

RADIO AND PHONOGRAPHIC AMPLIFYING RESONATOR.

Application filed April 26, 1923. Serial No. 634,816.

To all whom it may concern:

Be it known that we, WILLIAM C. LARSON and CHARLES P. WEGNER, citizens of the United States, residing at Two Harbors, in the county of Lake and State of Minnesota, have invented certain new and useful Improvements in Radio and Phonographic Amplifying Resonators, of which the following is a specification.

10 This invention relates to radio speakers and phonographs, and the primary object of the invention is to provide an improved horn or sound amplifying compartment, so constructed as to first, preserve the delicate overtones or partials and to prevent the damping or smothering thereof by the harsher fundamentals or full notes; second, to reflect back the sound waves into the sound chamber giving additional volume 15 to the overtones; third, the breaking up of prolonged or pronounced reverberations, which often cause, in vocal selections particularly, blurred or jumbled words; fourth, the return of filtered vibrations resulting in 20 the damping of short sound waves which are one of the principal causes of friction noises; fifth, the creation of a perfect balance in the functioning power of the various parts or segments of the horn resulting in the elimination of discordant 25 vibrations, and sixth, the giving of a sound of great volume, clear and mellow, resulting from the overlapping columns of sound waves passing to and fro in the horn.

30 Another prime object of the invention is to provide an improved horn or sound amplifying compartment surrounded by closed air chambers or compartments, the closed air compartments or chambers functioning 35 to insure the proper balance of tone, and to preserve the delicate overtones that would otherwise be damped out.

A further object of the invention is to provide a horn or sound amplifying compartment having each wall or segment thereof provided with a closed air chamber or compartment, which prevents the leakage of the sound waves from the tone or amplifying compartment or chamber.

40 A still further object of the invention is to provide an improved sound amplifying chamber or horn of the above character, which will be durable and efficient in use, one that will be simple and easy to manufacture, and one which can be incorporated

with the ordinary types of phonographs and radio speakers.

With these and other objects in view the invention consists in the novel construction, arrangement and formation of parts, as will be hereinafter more specifically described, claimed and illustrated in the accompanying drawings, forming a part of this specification in which drawings:

Figure 1 is a plan view of the improved 60 horn or sound amplifying member, the throat thereof being shown in section.

Figure 2 is a transverse section through the sound amplifying horn taken on the line 2—2 of Figure 1 looking in the direction 70 of the arrows.

Figure 3 is a similar section taken on the line 3—3 of Figure 1 looking in the direction of the arrows.

Figure 4 is a longitudinal section through 75 the improved horn taken on the line 4—4 of Figure 1.

Referring to the drawings in detail, wherein similar reference characters designate corresponding parts throughout the 80 several views, the letter A generally indicates the improved phonograph and radio sound amplifying horn. The sound amplifying horn A includes the main body portion 5 constituting the tone chamber and the upwardly extending arcuately curved 85 throat section 6, which is adapted to be connected in the ordinary manner with the tone arm of the phonograph (not shown) and base of a loud speaker.

The tone chamber 5 and the throat 6 are double walled and these walls form a continuation of one another so as to form a continuous and uniformly diverging sound conduit extending from the tone arm to the 90 outer end of the tone compartment. The inner wall 7 of the tone chamber 5 and the outer wall 8 thereof each includes four flat jointed side pieces formed of thin sounding board material, preferably of wood of the 100 quality and dimensions employed in violin or zither structures and which are numbered 9 and 10 respectively in the drawings. The side pieces 9 of the inner wall 7 have the upright portions thereof extended to the outer wall 8, as indicated by the reference character 10', thus defining independent chambers 12 and 13 at the sides of the horn and independent chambers 14 and 15 at the top 105 and bottom of the horn.

As stated, the walls of the throat 6 form a continuation of the walls of the tone compartment 5 and thus it can be seen that the inner converging ends of the inner and outer walls 7 and 8 of the tone compartment 5 are curved upwardly and inwardly as at 16 and 17. Connecting pieces 18 are employed at the front end of the horn to unite the walls 7 and 8 together and similar pieces 10 19 are utilized to connect the walls together at the outer end of the throat 6.

Openings 20 can be made in the extended portions 10 of the upright portion of the inner walls 9 at equidistantly spaced points, 15 so as to unite the chambers 12, 13, 14 and 15 together.

From the foregoing it can be seen that each wall or segment of the amplifying horn is provided with a chamber and thus 20 all sides of the horn are treated in a like manner, which insures the proper balance of tone and tends to preserve the delicate overtones that would otherwise be lost. It is of course essential that all sides of the 25 horn be treated the same, as vibrations or sound waves passing from the reproducer of the phonograph and through the tone arm are expanded into the resonance chamber evenly on all surfaces thereof.

30 It has been found that a horn constructed in the above manner will preserve the peculiar tone or timbre of each individual instrument, such as the flute, violin, and the like. The chambers 12, 13, 14 and 15 act 35 as members corresponding to the overtones developed in different instruments and will vibrate sympathetically and harmonically one with the other. In this manner discordant vibrations are to a great extent avoided, 40 and the sound produced will be of a pure and richer quality.

The horn will effectively prevent the filtering of vibrations through the resonator walls and thus prevent loss in the volume 45 of the sound in the tone chamber.

All of the side walls 7 of the improved amplifier are provided with harp-shaped openings 25. These openings play an important rôle in the horn, in that they improve the tonal qualities, by producing fibers of varying lengths which would assist in breaking up of prolonged reverberations and to improve the resonator from an artistic standpoint.

Changes in details may be made without departing from the spirit or the scope of this invention.

What we claim as new is:

1. A sound amplifying horn comprising a tone chamber and throat having a continuous sound conduit therethrough and including inner and outer spaced walls, end pieces connecting the walls together at the outer terminals of the throat and tone chamber, certain of the inner walls being extended to engage the inner surface of the outer walls to form independent compartments, said extended portions of the inner walls being provided with openings to establish communication between all of the compartments.

2. A sound amplifying horn comprising a tone chamber and a throat having a continuous sound conduit therethrough and including inner and outer spaced walls, the outer wall being formed of imperforate material, imperforate end pieces connecting the walls together at the outer terminals of the throat and tone chamber, certain of the inner walls being extended to engage the inner surface of the outer wall to form independent compartments, said extended portions of the inner walls being provided with openings to establish communication between all of the compartments, the inner walls at the tone chamber being provided with sound escape openings.

In testimony whereof we affix our signatures.

WILLIAM C. LARSON,
CHARLES P. WEGNER.
